CURTAIN ROD

Ledger D. Ford and Frederick L. Stutz, Sturgis,
Mich., assignors to Kirsch Company, Sturgis,
Mich., a corporation of Michigan

Application January 10, 1946, Serial No. 640,306

10 Claims. (Cl. 211—105.3)

1

The main objects of this invention are:

First, to provide a curtain rod having a combined bracket engaging tip and threading pilot which constitutes a permanent element of the rod which is effective for the purpose and at the same time is very economical.

Second, to provide a curtain rod structure having these advantages which is adapted for use with or readily engageable with different forms of brackets, for example, brackets adapted for supporting a plurality of curtain rods and brackets adapted for supporting single curtain rods and engageable from the top of one form of bracket or from the end of another form.

Third, to provide a curtain rod structure having these advantages which is very easily manipulated in the assembling of the combined rod engaging tip and pilot member and the assembling or engagement with the brackets.

Objects relating to details and economies of the invention will definitely appear from the description to follow. The invention is defined in the claims.

A structure which embodies the features of the invention is clearly illustrated in the accompanying drawing, in which:

Fig. 1 is a fragmentary plan view of curtain rod assembly illustrating our invention as embodied in a multiple rod assembly.

Fig. 2 is a fragmentary view partially in section on line 2—2 of Fig. 1.

Fig. 3 is a perspective view of the combined bracket engaging tip and threading pilot element.

Fig. 4 is an enlarged fragmentary view in section on line 4—4 of Fig. 3.

Fig. 5 is a fragmentary plan view of an adaptation of our invention to another form of supporting bracket.

Fig. 6 is a fragmentary front view of the structure shown in Fig. 5.

Fig. 7 is a perspective view of the bracket of Figs. 5 and 6.

The embodiment of the invention illustrated comprises a tubular curtain rod 1 of oval or non-circular section formed of sheet stock rolled or folded upon itself. The combined bracket engaging tip and threading pilot designated generally by the numeral 2 comprises a convex head 3 of peripheral shape corresponding substantially to the shape and dimensions of the rod; that is, when the rod is of oval section the head is correspondingly of oval section.

The rod tip member has neck members 4, 4 extending from opposite edges thereof, these neck members being of a width less than the larger dimension or greatest diameter of the head and merging into the convex or round face of the head, the neck members having integral spring arms 5 extending from their inner ends. These arms are of convexly curved section frictionally

2

fitting within the rod, that is, they are in frictional retaining engagement with the rod. The arms are inwardly offset from the neck members as best shown in Figs. 3 and 4 providing inwardly facing shoulders 6 which abut the end of the rod, thus insuring the proper position of the bracket engaging tip member relative to the rod. It will be understood that each end of the rod is provided with a tip member although only one would be required for use as a threading pilot. The structure is so economical, however, and its bracket engaging functions so desirable, that it is advantageous to use the same tip member at both ends of the rod.

The tip members are adapted for engagement with different types of brackets; in Figs. 1 and 2 for example we illustrate a bracket 7 of considerable length having attaching ears or flanges 8 at its inner end. This bracket is of angular section and is positioned to provide an upstanding arm 9 and a horizontal arm 10 at the bottom thereof. The upstanding arm 9 is vertically slotted at 11, the slots being spaced to provide upwardly projecting tongues 12 adapted to be received between the neck members 4, 4 of the tip. The slots are of such depth that the rod 1 rests on the bottom flange 10 of the bracket. This relieves the tip of undue stress or load when the rod is engaged with the bracket.

In the adaptation shown in Figs. 5, 6 and 7 the bracket 13 is provided with an attaching flange 14, the projecting arm portion of the bracket having a longitudinal slot 15 therein adapted to receive the neck members of the tip when they are presented edgewise thereto as shown in Figs. 5 and 6. In this case the entire load of the curtain is carried by the tip.

To retain the curtain rod within the bracket, spring tongues or fingers 16 are provided which are formed from the portion of the arm of the bracket struck out to form the slot 15. The tongue or finger is curved to embrace the curved head as shown in Figs. 5 and 6 and thereby releasably retain the curtain rod in engagement with the bracket, the head of the tip engaging under the one with a spring or snap action. The rounded or convex head of the tip serves as an effective pilot for threading the rod through the hem of a curtain without injury to the fabric, the head deflecting the curtain fabric from the end of the rod. The springable retaining fingers present a substantial frictional area for engagement with the rod so that the tip members are effectively frictionally retained therein, and this even though the rod and tip members may be made of comparatively light gauge stock. The tip members are formed of flat pieces of sheet stock folded and cupped centrally to provide the head which is concavo convex. Portions of the stock are cut away at opposite edges thereof to

provide a neck member 4. The spring arms are cross sectionally conformed to the curtain rod. While curtain rods vary somewhat in cross sectional shape and dimensions, the oval cross section substantially as illustrated is well known and widely used. This non-circular cross section is a desirable shape for use with the rod tips of this invention as it is important to have the tips in non-rotative engagement with the rods.

We have illustrated and described the invention in highly practical commercial embodiments thereof. We have not attempted to illustrate various modifications and adaptations as it is believed this disclosure will enable those skilled in the art to embody or adapt the invention as may be desired.

Having thus described the invention what is claimed as new and desired to secure by Letters Patent is:

1. The combination with a tubular curtain rod of non-circular section, of a combined bracket engaging tip and threading pilot comprising an oval convex head, spaced neck members extending inwardly from the longer edges of the head, the width of the neck members being substantially less than the longer dimension of the head, and convexly curved spring arms extending from the neck members and springably fitting within the rod, the spring arms being inwardly offset relative to the neck members providing shoulders abutting the end of the rod, the peripheral dimension of the head substantially corresponding to that of the rod.

2. The combination with a tubular curtain rod of non-circular section, of a combined bracket engaging tip and threading pilot comprising an oval convex head, spaced neck members extending inwardly from the longer edges of the head, the width of the neck members being substantially less than the longer dimension of the head, and spring arms extending from the neck members and springably fitting within the rod, the peripheral dimension of the head substantially corresponding to that of the rod.

3. The combination with a tubular curtain rod of a combined bracket engaging tip and threading pilot comprising a convex head, neck members extending from opposite edges of the head, the head projecting beyond the edges of the neck members, and curved spring arms extending from the neck members and frictionally engaged within the rod, the spring arms being inwardly offset relative to the neck members providing shoulders abutting the ends of the rod, the peripheral dimension of the head substantially corresponding to that of the rod.

4. The combination with a tubular curtain rod of a combined bracket engaging tip and threading pilot comprising a convex head, neck members extending from opposite edges of the head, the head projecting beyond the edges of the neck members, and spring arms extending from the neck members and frictionally engaged within the rod, the peripheral dimension of the head substantially corresponding to that of the rod.

5. The combination with a tubular curtain rod of a combined bracket engaging tip and threading pilot comprising a rounded head, spaced bracket engaging neck members extending from opposite edges of the head portion and having integral arms extending from their inner ends, said arms having frictional retaining en-

gagement within the rod, the rod engaging arms being inwardly offset relative to the neck portions providing shoulders abutting the ends of the rod, the peripheral dimension of the head substantially corresponding to that of the rod.

6. The combination with a tubular curtain rod of a combined bracket engaging tip and threading pilot comprising a rounded head, and spaced bracket engaging neck members extending from opposite edges of the head portion and having integral arms extending from their inner ends, said arms having frictional retaining engagement within the rod, the peripheral dimension of the head substantially corresponding to that of the rod.

7. The combination with a curtain rod, of a combined bracket engaging tip and threading pilot comprising a curved head, and spaced bracket engaging neck members extending from opposite edges of the head, a part of the head projecting beyond the neck members and being adapted to overlap a side of a bracket having slots therein receiving the neck members, the neck members having integral spring arms extending therefrom frictionally engaged with the rod.

8. The combination with a curtain rod, of a combined bracket engaging tip and threading pilot comprising a curved head, and spaced bracket engaging neck members extending from opposite edges of the head, the neck members having integral spring arms extending therefrom frictionally engaged with the rod.

9. The combination with a bracket having an inturned flange on its lower edge and spaced slots in its upper edge providing an upwardly projecting tongue, of a curtain rod, and a bracket engaging tip having a threading pilot head, neck members extending from the head and spaced to receive said tongue on said bracket between them, said neck members having arms extending therefrom and retainingly engaged with the rod, the rod being supported by said bracket flange when the tip is in engagement with said tongue thereof.

10. The combination with a bracket having spaced slots in its upper edge providing an upwardly projecting tongue, of a curtain rod, and a bracket engaging tip having a threading pilot head, and neck members extending from the head and spaced to receive said tongue on said bracket between them, said neck members having arms extending therefrom and retainingly engaged with the rod.
